UNITED STATES PATENT OFFICE.

MARK S. HOTCHKISS, OF JOHNSON CITY, NEW YORK.

METAL SPOOL.

Application filed July 14, 1925. Serial No. 43,513.

My invention relates generally to spools and particularly to that type adapted for the spooling of wire such as fence wire, rope, metal strips or the like. These uses to which my invention may be put are mentioned as illustrative only, as the spool is adapted for a wide variety of uses in many arts.

The principal object of my invention is to construct a metal spool which is steady and rigid in construction, inexpensive to manufacture and which may be readily assembled.

Another object is to form the flanges of this spool from two metal cross pieces which are securely held in their assembled relation by means of the cross pieces forming the spool core or dowel.

A further object is to provide means on the end of the cross pieces forming the core, to secure the flanges in their assembled relation.

A still further object is to provide means on the ends of the cross pieces forming the flanges of the spool, whereby a coil of wire, rope or other material which is wound upon the spool, may be securely held in its place without danger of unwinding.

Other objects and advantages in details of construction and operation will be apparent as the description proceeds reference being had to the accompanying drawing wherein like reference numerals indicate like parts.

35 In the drawing:

Figure 1 is an end view of my improved spool with a coil of wire or other suitable material wound thereon.

Figure 2 is a cross section of my improved spool taken on the line 2—2 of Figure 1, the coiled material having in this instance been omitted for clearness in illustration.

Figure 3 is a detail showing the manner in which the cross pieces forming the core or dowel of the spool cooperates to secure the flanges in position.

Figure 4 is a detail of one of the pieces forming the flanges of the spool.

Figure 5 is a detail showing in the flat, one of the cross pieces forming the core of the spool.

My improved spool is preferably constructed of sheet metal and is of such formation that all of the parts thereof may be easily and readily stamped from a piece of

material and then formed for cooperative relation with each other to provide the spool.

The reference numeral 1 indicates the strips or pieces of metal or other suitable material which form the flanges of the spool; 60 two of these strips are provided at each end of the spool, and are laid crosswise on each other, intersecting at the center.

Each strip is provided on opposite sides of its center with small recesses 2. These recesses are spaced apart a sufficient distance to just clear the edges of the adjacent strips 1, and receive a tongue 3 formed at the ends of cross pieces 4, preferably stamped also from sheet metal, and providing the core or dowel of the spool. The cross pieces 4 are provided with flanges 5 bent inwardly so that there will be no sharp edges presented to the wire or rope which may be wound upon the spool. 75

The tongues 3 pass through the recesses 2 in the strips 1 and are then bent inwardly over the edges of the adjacent flange strip 1, to securely hold the same in its assembled position. 80

The ends of the strips 1 may be scored or weakened as at 6, whereby said ends may be easily bent inwardly as illustrated in dotted lines in Figure 2, to prevent the unwinding of the wire or other material wound upon the spool. The strips 1 are preferably formed of such material as will readily permit this bending action. 85

An opening 7 is provided in the center of each of the flanges 1 to receive a shaft or spindle upon which the spool may be rotated by any suitable means such as a pulley or friction device for winding or unwinding the material upon the spool. A small opening 8 may also be provided in the flange pieces 1 at a point adjacent the periphery of the core or dowel through which may be passed one end 9, of the wire or other material 10 wound upon the spool. 95

It will be noted that this spool offers a very attractive manufacturing proposition in that the four strips 1 forming the flanges are all identical, and the four strips 4 constituting the core or dowel of the spool are also identical. These eight pieces are all that are necessary to form the spool. 100

The operation of my invention is as follows: The spool is mounted upon a suitable shaft and one end of the wire or rope to be wound upon the spool is inserted through 110

the opening 8, and the spool rotated by any standard and suitable means such as a friction pulley, or other device, thus winding the material upon the core of the spool. When the desired length of material has been wound upon the spool, the ends of the flanges 1 may be bent down over the material to secure it against unwinding.

When it is desired to draw the material off of the spool for use, it is necessary only to bend up the end pieces of the flanges 1, as shown in Figure 2, and again if desired, mount the spool upon a pulley, shaft or spindle whereby it will rotate freely and permit the drawing off of the wound material.

I do not limit myself to the exact construc-

tion or materials herein shown and described other than by the appended claims.

I claim:

1. A spool comprising flanges composed of intersecting flat strips said strips being provided with recesses adjacent the points of intersection, a core having integral tongues in said recesses and overlapping the adjacent strip.

2. A spool comprising flanges composed of intersecting flat strips, a core composed of channel pieces extending between said flanges and provided with tongues passing through said flanges and overlapping the adjacent strip to prevent the separation of the flanges and to secure said strips together.

MARK S. HOTCHKISS.
